UNITED STATES PATENT OFFICE.

ALFRED R. OBERWEGNER, OF TOLEDO, OHIO.

WASHING MACHINE.

Application filed October 20, 1927. Serial No. 227,382.

My invention has for its object to provide a washing machine wherein a centrifugal drier used for removing water from the clothes may be so supported as to reduce the floor space normally occupied by the machine when not in use. In this connection the invention also provides a means for automatically making connection with the driving mechanism when it is moved into position for use, means, however, being provided for disconnecting and connecting the drier with the driving means.

The invention has for its object other advantages and features which will appear on examination of the drawings forming a part hereto, and from the description appended hereto.

The invention may be contained in washing machines of different forms, and to illustrate a practical application of the invention, I have selected a washing machine containing the invention as an example of such structures and shall describe it hereinafter. The structure referred to is shown in the accompanying drawings.

Fig. 1 is a perspective view of the washing machine showing the centrifugal drier in a folded or closed position. Fig. 2 is a sectional view of a water collector for collecting the water that is centrifugally removed from the clothes in the drying operation. Fig. 3 illustrates a detail for disconnecting the drier from the driving mechanism. Fig. 4 is a sectional view showing the connecting parts of the washing machine. Fig. 5 is also a sectional view illustrating a detail of the driving mechanism. Fig. 6 is a view of the cover of the washing machine and a top view of the centrifugal drier which is mounted in the cover.

The particular washing machine that I have selected as an example of the various forms of washing machine to which my invention may be applied, is of a type well known wherein a centrifugal oscillating member, having one or more wings, operates to agitate the clothes and by their movement through the water cause the removal of the dirt in the manner well known in the art. The oscillating member is operated by a suitable electric motor, which also may be used in the constructions embodying my invention, to drive the drier. Also, such machines are usually provided with a cover for closing the interior of the tub of the machine.

In the particular form of construction shown in the drawings, the washing machine

1 is provided with a cover 2 that is hingedly connected to the tub 3 of the machine so as to enclose the interior of the tub. The bottom 4 of the tub is inverted pyramidal or conical in form to normally cause the clothes to slide towards the center of the bottom. A plurality of oscillatable members 5 that extend radially in the form of wings, from a central sleeve 6, are supported on and connected to a spindle 7 that extends through the central part of the bottom of the tub. If desired, a dish shaped plate 8 may be located beneath the wings 5 and in spaced relation to the central part of the bottom 4. The spindle 7 is operated by a reciprocating rack 10 and a pinion 11. The pinion 11 is connected to the spindle 7, while the rack 10 is connected to a crank 12. The crank 12 is connected to a shaft 13 that is pivotally supported in a suitable platform 14 and in a boss 15 formed in a housing 16. A worm gear 17 is keyed to the shaft 13 and is driven by a worm 18 that is connected to the motor 19.

When the clothes have been sufficiently worked by the washing machine to remove the soil from the clothes, they are, as is well known, run through a wringer or a centrifugal drier. In the construction embodying my invention, I have provided a cover 2 that is hingedly connected to the top of the tub of the washing machine, and the drier is mounted in the cover 2. The drier is in the form of an inverted frustum shaped, rotatable receptacle 21. The upper edge of the receptacle is curved inwardly as at 22 and the edge portion is perforated as at 23. When, therefore, the receptacle 21 is rotated at a relatively high speed, the water will be carried up the inclined, or frustum, wall, and pass out through the openings formed in the inwardly curved edge portion 22 of the receptacle.

In order to collect the water that is thus thrown from the receptacle, a split annular member 25 is supported on the cover 2. The annulus 25 is, preferably, formed of two parts that are clamped together by bolts 26 that extend through flanges 27 that are formed at the ends of the parts of the annulus. The annulus has a curved inturned edge portion 32 that, preferably, overlies the inturned edge portion 22 of the receptacle and is provided with a channel 28 that is formed between a ridge 29 and the curved wall of the annulus. The annulus 25 is provided with a mouth 30 to permit the discharge of the water that is collected in the channel 28. Prefer-

ably, the cover 2 is provided with a laterally extending flange 31 that fits into a groove formed in the outer edge portion of the annulus and on which the annulus 25 may be rotated so as to locate the mouth 30 of the annulus in different positions with respect to the receptacle. Thus the mouth 30 may be located so as to deliver the water, that is gathered in the channel 28, back into the tub 10 or may be so located as to deliver the water outside of the tub and into a suitable pail or other container, as the receptacle is being rotated and the water is directed through the openings 23 and into the channel 28.

15 The receptacle 21 is rotated by means of a friction disc 35 that operates on a ring 36 located on the lower edge of the receptacle. The ring 36 rests against the edge of the disc 35 which is rotated by means of the motor 19, 20 operating through the shaft 13, to which it is connected by the bevel gears 37 and 38. The disc 35 is slip keyed to a shaft 39 which is connected to the bevel gear wheel 38 and is supported on the end of the bracket 40 that is 25 connected to the boss 15 formed on the housing 16. A spring 24 is located intermediate the disc 35 and the bracket 40. The spring operates to take up the vibration that would otherwise be produced by the speed of the 30 rotation of the drier, particularly, when loaded with clothes unevenly. The receptacle is rotatably supported on the cover by means of a pin 44 that is located in an end thrust bearing 41 positioned in a U-shaped 35 bracket 42 that is secured to, or formed integral with, the cover 2. The upper end of the receptacle is also guided in its rotation by the cover and the outer edge portion of the annulus 25. The receptacle 21 is provided with 40 a lip 43 that extends over the ridge 29 which coacts to hold the receptacle in its rotative position, and also operates to deliver the water, that is ejected through the perforations in the inturned edge portion 22 of the 45 receptacle 21, into the channel 28, and thus prevent the escape of water between the receptacle and the cover 2.

When the drier is in operation, the weight of the cover, the receptacle, and the clothes, 50 presses the ring 36 against the disc 35 whereby good frictional contact is made and good driving connection is established. When it is desired to remove the clothes from the drier, the driving connection with the electric 55 motor may be discontinued by means of a cam 45 that is rotatably supported in a bracket 46 secured to the side of the tub 3 of the machine. The cam 45 is connected to the rod 47 that extends to one corner of the tub and is rotatably supported in the brackets 46 and 48. The 60 rod 47 may be provided with a handle 49 whereby the rod 47 may be conveniently rotated to rotate the cam 45. The U-shaped bracket 42 of the cover 2 is provided with a 65 U-bar 50 that partially surrounds the drier

and in position so as to be engaged by the cam 45 to move the ring 36 away from the friction disc 35 when the handle 49 is rotated. Thus the driving connection with the motor 19 may be easily established and disconnected 70 by manipulation of the cam 45.

When the washing has been completed, the cover may be closed which inverts the drier and locates it above the tub 3.

I claim:

1. In combination with a washing machine and a driving mechanism therefor, a centrifugal drier hingedly connected to the machine and a means for establishing driving connection with the driving mechanism in a swing 80 position of the drier.

2. In combination with a washing machine and a driving mechanism therefor, a rotatable member connected to the driving mechanism, a centrifugal clothes drier hingedly connected to the machine and a means for rotatably connecting the drier with the rotary member in a swing position of the drier.

3. In combination with a washing machine and a driving mechanism therefor, a centrifugal clothes drier pivotally connected at one side of the drier to the washing machine, and a means for connecting the drier to the driving mechanism in a swing position of the drier about its pivotal support.

4. In combination with a washing machine and a driving mechanism therefor, a cover for covering the tub of the washer and hingedly connected with the washing machine, a centrifugal drier supported on the cover, a rotatable member connected to the driving mechanism, and a means for rotatably connecting the drier with the member when the cover is swung to open the tub.

5. In combination with a washing machine and a driving mechanism therefor, a cover for covering the tub of the washer and hingedly connected with the washing machine, a centrifugal drier supported on the cover, a friction disc to rotate the drier connected to the driving mechanism, a means for rotatably connecting the drier with the friction disc when the cover is swung open, the drier having an inverted frustumal shaped receptacle and an annulus for collecting the water that is centrifugally forced from the upper end of the receptacle.

6. In combination with a washing machine and a driving mechanism therefor, a cover for covering the tub of the washer and hingedly connected with the washing machine, a centrifugal drier supported on the cover, a friction disc to rotate the drier connected to the driving mechanism, a means for rotatably connecting the drier with the friction disc when the cover is swung open, and a manually operated means for disconnecting the drier from the disc.

7. In combination with a washing machine and a driving mechanism therefor, a cover

for covering the tub of the washer and hingedly connected with the washing machine, a centrifugal drier supported on the cover, a friction disc connected to the driving mechanism, a means for rotatably connecting the drier with the friction disc when the cover is swung open to rotate the drier, the drier having an inverted frustum shaped receptacle, an annulus for collecting the water that is centrifugally forced from the upper end of the receptacle, and a spring for yieldingly pressing the disc against the drier.

8. In combination with a washing machine and a driving mechanism therefor, a cover

for covering the tub of the washing machine 15 and hingedly connected with the washing machine, a centrifugal drier supported on the cover, a friction disc to rotate the drier connected to the driving mechanism of the washing machine and adapted to engage the centrifugal drier when in a swung position, and a spring for yieldingly resisting the movement of the disc by the pressure produced by the drier.

In witness whereof I have hereunto signed 25 my name to this specification.

ALFRED R. OBERWEGNER
